UNITED STATES PATENT OFFICE.

JOHN M. RUSBY, OF PHILADELPHIA, PENNSYLVANIA, ASSIGNOR TO THE U. G. I. CONTRACTING COMPANY, OF PHILADELPHIA, PENNSYLVANIA, A CORPORATION OF DELAWARE.

METHOD FOR GASIFICATION OF BITUMINOUS COAL.

Application filed June 7, 1923. Serial No. 643,859.

The principal objects of the present invention are, first, to effect the complete or partial gasification of bituminous coal or like material in a single bed and therefore 5 in one vessel; second, to use that fuel in such a way that its valuable volatile portion will be conserved in substantially its entirety; third, to effect the carbonization substantially solely by contact with blue water gas; 10 fourth, to assure a sufficiently high temperature of the blue gas for effecting the carbonization; and sixth, to prepare unusually refractory or wet fuel for carbonization by drying and preheating. Other objects of 15 the invention will appear from the following description.

The invention may be said to consist in the method of gasifying bituminous coal and the like which comprises establishing 20 a descending fuel bed at the top of which such coal is fed and carbonized to coke, alternately heating the entire cross-section of the coke by blasting it from the bottom to the top and from the top to the bottom 25 thereby providing two separate hot zones in the fuel bed and beneath the coal, intermittently generating blue water gas in the lower zone by blasting the fuel bed upward with steam, superheating the blue gas by 30 passing it through the upper zone, and carbonizing the coal to coke substantially solely by the superheated blue water gas.

The invention also comprises the method above described with the additional step of 35 preheating the soft coal prior to carbonization by circulating gas through the hot zones and through the freshly charged coal.

The invention also comprises the improvements to be presently described and finally 40 claimed.

In the following description reference will be made to the accompanying drawings forming part hereof and in which

Figure 1 is an elevational view, partly in 45 section, of apparatus embodying features of the invention and adapted for the practice of the method of the invention and

Fig. 2 is a similar view illustrating a modification and showing in a highly dia- 50 grammatic fashion an illustration helpful in the description of the method.

Referring to the drawings *a*, *b*, *c* and *d*, indicate a descending fuel bed at the top of

which bituminous coal or the like is fed, and this coal is carbonized to coke as at *a* solely 55 by blue water gas and the coke may be taken to be represented generally at *b*, *c* and *d*. The coke is blasted with air alternately from the bottom to the top and from the top to the bottom, in a manner that will be presently described, thereby providing separate 60 hot zones, *b* and *d*, in the fuel bed. The zones are referred to by reference letters *b* and *d* for the sake of description and not to indicate precise location or extent. Alternately with the air blasting step water gas is generated in the lower coke zone *d* by 65 blasting the entire fuel bed (coke and coal) upward with steam, and the blue water gas generated at *d* is raised to an appropriate 70 temperature for carbonizing the coal at *a* by passing the blue water gas generated at zone *d* through the heated zone *b*, and then through the coal, so that the coal at *a* is carbonized by the superheated blue water 75 gas. The resultant gas (water gas and coal gas) is led off from *a* by 17, 18 and 19 for use for any purpose.

The water gas generator consists of a single vessel 1 enclosing the carbonization 80 chamber 2 and an underlying gasification chamber 3 in communication with the chamber 2. 4 is a grate arranged in the chamber 3. 5 is an air blast main which by way of the valves 6 and 6^a discharges blast either 85 through the ports 7 to the top of the chamber 3 or by the connection 8 to the bottom of the chamber 3. When air blast is directed downward from the top to the bottom of the chamber 3 the connection 9 is 90 closed by the valve 10 and the outlet from the bottom of the chamber 3 is by way of 8 either to the stack 11 or to the pipe 12 according to the position of the valves 13 and 14. Usually the air blast gas is led off 95 from 12, for use either in a waste heat boiler or in an apparatus for carbureting water gas. Neither of these is shown because they are too well understood to require description or illustration. When air blast is directed upward from the bottom to the top of the chamber 3 the valve 6 is closed, the valve 6^a is open to let air pass from 5 to 8, and valve 10 is in position to close the connection 8 and to open the connection 9, 100 105 and the blast passes downward through the

connection 8 up through the chamber 3 and by the ports 7 to the connection 9 from which the blast gas is passed either to the stack 11 or to the connection 12 according 5 to the position of the valves 13 and 14. 15 is a steam connection for blasting with steam upward through the chamber 3 and through the chamber 2 and passing the resulting gas to the off-take 16 by way of the 10 pipe 17, branch 18 and seal box 19, the valve at 20 being open. The valves 6 and 6^a are closed and the pipe 9 is closed by the valve 10. The pipes 17, 21, impeller 22, pipe 23 and check valve 24, provide a means for 15 continuously circulating gas from the top of the chamber 2 to the bottom of the chamber 3 and then to the top of the chamber 2. 25 is a stirrer. 26 is a branch connection provided with a valve 27 and its purpose is 20 to provide for the recovery of valuable hydrocarbons that may be driven off from the bituminous coal as will be described.

The carbonizing of the coal is done in 2, whence it descends as coke to 3. 3 is air 25 blasted upwardly establishing a hot zone at about *d*. The blast products pass off at the ports 7 as has been described. Thereafter for a brief period the air blast from 5 and 6 is applied through the ports 7, downward 30 through the fuel in 3, thus establishing an intensely hot zone at about *b*. The blast products pass off as has been described that is, from the bottom of the chamber 3 by way of 8 either to the stack 11 or to the pipe 12 35 according to the position of the valves 13 and 14. Steam is then admitted at 28 (shown in Fig. 1 but not in Fig. 2, because in Fig. 2 the wall that carries it is not shown) resulting in the rapid production of 40 blue water gas, though of comparatively low temperature, at the zone *d*, which gas thereafter rises and is highly superheated in the zone *b*. This superheated water gas is forced upward through the bituminous coal 45 at *a*, and the mixture of blue water gas and evolved coal gas is discharged through the seal box 19 and offtake 16 to a holder or otherwise appropriately disposed of.

If the freshly charged bituminous coal at 50 the top of 2 is wet or if the coal is unusually refractory to carbonization, then, and preferably immediately, after charging the fresh coal the gaseous contents of the generator is caused to circulate by the impeller 22 and 55 its connections up through the hot fuel bed in chamber 3, there heated and then discharged upward through the coal in the chamber 2 whereby the latter is dried and heated; during this circulation of course all 60 valves for admission of air or steam or for exit of gases to the atmosphere or elsewhere are closed so as to seal the entire generator to anything but the just described circulation of gas, except that whatever surplus gas 65 may be produced in this circulation process

will be continuously discharged through 18 and 19 to the gas holder or elsewhere as desired. This circulation can be continued to whatever extent is desirable. If this recirculation be done with proper attention to 70 the temperature of the hot fuel bed in 3, whatever volatile matter from the coal is thus recirculated need not be seriously injured thereby; the temperature of the fuel bed can be controlled, as necessary, by alternating the above described air blasting and blue water gas making operations with this recirculation. The gas thus drawn from the top of the generator and recirculated is sufficiently low in temperature to be easily handled by an impeller 22 of any well known type.

The device 25 is provided for agitating, periodically or continuously as may be desired, the bituminous coal. This maintains 85 the freshly charged coal open and freely permeable to the hot blue water gas and also breaks up and renders thus porous the coke formed in the process of carbonization.

29 are openings or stoke holes through 90 which bars may be inserted for assisting the descent of the fuel, for removing clinkers, and for stoking the fire. 30 is a means for supplying fresh coal to the generator.

Although the carbonization of the bituminous coal in 2 will be accomplished almost entirely during the actual passage of water gas therethrough, there may nevertheless be a small amount of distillation of volatiles from the coke, by accumulating heat during 100 the time that 3 is being air blasted and no gas is passing through the coal in 2. Should it be desired to conserve even this small amount of volatile matter the small valved connection 26 is availed of and the opening 105 of this passage to any desired and controllable extent will permit the discharge through the top of 19 and thence through 16 to the holder, of this evolved volatile matter.

The foregoing describes apparatus for the 110 production of mixed blue (uncarbureted) water gas and coal gas. Should it be desired to carburet this mixture of blue gas and coal gas the connection 31 shown in Fig. 2 diagrammatically represents the change 115 necessary in the apparatus shown in Fig. 1. Referring to Fig. 2 the pipe 12 is connected to the inlet of the carbureting vessel of a carbureted water gas set and is used for the passage of the air blast gas thereto, and the connection 31 serves for the passage of the mixed blue water gas and coal gas to that vessel. In the modification shown in Fig. 2, the seal box 19 and its connections as shown in Fig. 1, will not be as there arranged but will be transferred to the outlet 120 of the carbureting vessel which is its usual and well understood location in carbureted water gas apparatus. Of course the pipe 12 of Fig. 2 may be used for delivering a mix- 125 130

ture of air blast gas and blue water gas and coal gas and it also can be used to deliver gas to the inlet of a waste heat boiler.

It may also be pointed out that the air blasting alternately from the top to the bottom, and from the bottom to the top of the chamber 3, results in comparative uniformity of heating and other effects through the entire cross-section of the coke in the regions where the air blast is applied.

The foregoing described method of providing the upper hot zone "b" by down blasting with air is the preferable method, this insuring the greatest uniformity of temperature throughout this zone *b*. This hot zone can, however, be produced by supplying air blast by the inlets 32, of valved blast branch 33, the blast products being discharged upward through the ports 7 and the connection 9. And such blasting can either be done in alternation with the upward blasting through the grate 4, or can be done in conjunction with this upward blasting; in the latter case, the combustible producer gas issuing upward from the zone *d* will be in part burned and its heat utilized in heating the zone *b*.

The foregoing description refers to the production of a mixed blue water gas and coal gas which is substantially free from incombustible diluents, especially nitrogen. It is, however, sometimes desired to produce a blue water gas which is mixed with more or less ordinary producer gas which contains incombustible diluents, chiefly nitrogen. In case this mixture is to be produced the desired quantity of blast, or "producer", gas from the upward blasting of 3, will be diverted from passage through the ports 7, 9 and 13, to the atmosphere and will instead be passed upward through 2, and thence through 17, 19 and 16 to the holder, or else through 31 and 12 to the carbureted water gas alluded to in connection with Fig. 2. It is evident that in such case the upper hot zone of my process is of great value in superheating this producer gas before its discharge through 2, thus assisting in the carbonization of the bituminous coal. It is evident that this supplying of producer gas through 2 and thence to the gas holder, can be done either in conjunction with the production of blue water gas in 3 or can alternate with it, and also that the percentage of producer gas, thus supplied to the holder, or to a carbureted water gas set or other

desired point of storage or use, can be made whatever is desired.

It will be obvious that the invention is not limited to details of procedure and construction, or to mere matters of form, or otherwise than as the prior art and the appended claims may require:

I claim:

1. In the method for the complete gasification of bituminous coal in a single vessel; the improvement which consists in maintaining a descending fuel bed at the top of which is uncarbonized coal and at the bottom of which is coke immediately supporting the coal, establishing a bottom hot zone across the entire horizontal area of the coke by air-blasting the coke from the bottom of the coke upward, establishing a second and upper hot zone in the coke immediately supporting the uncarbonized coal by applying to the coke a second independent air-blast at that point, excluding the blast gas from the uncarbonized coal, then generating blue water gas by upwardly steam blasting the coke at the lower hot zone, passing the blue water gas thus formed upward through the upper hot zone whereby the blue water gas is highly heated, and then passing the highly heated blue water gas upward through the superposed coal to effect its carbonization to coke.

2. In the method for the complete gasification of bituminous coal in a single vessel; the improvement which consists in maintaining a descending fuel bed at the top of which is uncarbonized coal and at the bottom of which is coke immediately supporting the coal, establishing a bottom hot zone across the entire horizontal area of the coke by air blasting the coke from the bottom of the coke upward, establishing a second and upper hot zone in the coke immediately supporting the uncarbonized coal by applying to the coke a second independent downwardly directed air blast at that point, excluding the blast gas from the uncarbonized coal by leading it off at the bottom of the coke, then generating blue water gas by upwardly steam blasting the coke at the lower hot zone, passing the blue water gas thus formed upward through the upper hot zone whereby the blue water gas is highly heated, and then passing the highly heated blue water gas upward through the superposed coal to effect its carbonization to coke.

JOHN M. RUSBY.
